UNITED STATES PATENT OFFICE.

JOHN C. MARTINE, OF NEW YORK, N. Y.

COIN HOLDER.

Application filed April 21, 1925. Serial No. 24,774.

The present invention relates to a combination savings-bank and coin-holder, and it is the principal object of my invention to provide a receptacle in which a savings-
5 bank is combined with a coin or token holder that may conveniently be carried on the person and which allows a ready dispensing of the coins one at a time.

Another object of the invention is the provision of a combination savings-bank and coin holder and dispenser allowing a ready deposition and withdrawal of the coins.

A further object of the invention is the provision of a combination savings-bank and coin holder having means for advancing the coins to be dispensed one by one.

A still further object of the invention is the provision of a combination savings-
20 bank and coin holder or dispenser having novel and improved means for holding the coins in position and allowing a ready withdrawal of the outermost coin.

It is also one of the objects of my invention to provide a combination receptacle of this character allowing the ready deposition of coins into the savings-bank and coin holder, and a ready inspection of the number of coins held in the coin holder, and removal of the coins deposited in several layers in the receptacle.

These and other objects and advantages of my invention will become more fully known as the description thereof proceeds, and will then be specifically pointed out in the appended claim.

In the accompanying drawing forming a material part of this disclosure:

Fig. 1 is a sectional front elevation of the combination savings-bank and coin holder and dispenser constructed according to the present invention.

Fig. 2 is a side edge view thereof.

Fig. 3 is an end view thereof.

Fig. 4 is an end view seen from the opposite end.

Fig. 5 is a section on line 5—5 of Figure 1.

Fig. 6 is a section on line 6—6 of Figure 1.

Fig. 7 is a detail view illustrating the means for holding the coins, in the dispenser, in position, allowing a withdrawal of them, one by one.

The device comprises a casing 10 of any desired form and material, divided into two compartments 11 and 12, the compartment 11 of which, is serving as a savings-bank

while the compartment 12 is serving as a coin or token holder and dispenser.

A partition wall or channeled stop 13 separates the two compartments and co-
operates with the channeled side wall stop 14, in the compartment 12, to guide the coins or tokens 15.

One of the end walls of the casing 10 is depressed and curved as at 16 and provided with a slot through which the outermost coin is partially projected ready to be gripped by the fingers.

The coins are arranged in two superposed layers and are advanced towards the opening in the end wall 16 by means of fingers or plungers 17, gripping over the innermost coins and which are attached to a guide socket 18, adapted to slide along the strip or partition 13 under the action of springs 19 attached at one end to said socket or guide 18 and guided over a suitable double-pulley 20 rotatably secured on a pin 21 in the side wall of the savings compartment 11. The other ends of the springs are secured to suitable eyes 22 provided on the inner face of the rear edge wall of the casing.

The outermost coins 15 are held against accidental displacement and prevented from falling out of the same by means of plates 23, pressed against the margin of the outermost coin by means of a spring or springs 24 secured to the partition wall or strip 13.

Star-shaped openings 25 or openings of any other suitable shape are formed in the side walls of the coin-holder to allow a ready inspection of the number of coins held therein.

The savings-bank compartment 11 has in one of its end walls a slot 26 for the deposition of the coins and at its opposite end a door 27, closed by a latch 28, adapted to be operated by a key to be inserted into the key-hole 29, in order to allow a removal of the coins 30 of various denomination.

It will be clear that the coins 15 are constantly pressed by means of the fingers 17 toward the opening, so that the outermost coin will protrude partly through said openings and can conveniently be gripped by the fingers. The spring controlled plate 23 engaging the outermost coin, will prevent the coins from falling accidentally out of the holder 12.

The inspection openings 25 will at any time, allow a counting of the number of coins held in the holder 12, and if all of the

coins therein are used, the receptacle can be filled again with suitable coins from the savings compartment 11 by simply pressing the coins inwardly.

5 It will be apparent, that the device described can be changed in its arrangement or in the construction of the minor details, such as fall within the scope of my invention, without departure from the spirit thereof as defined in the appended claim.

10 Having thus described my invention, what I claim as new, and desire to secure by Letters Patent, is:

15 The combination, in a device of the class described, of a casing having an opening near the upper end, guide members support-

ed at their extremities by said casing, allowing lateral clearances between said guide members, plungers slidably mounted on the said guide members, pulleys rotatably mounted in said casing, springs acting over said pulleys, and having one of their ends attached to said plungers, and the other of their ends to the said casing, normally urging said plungers to one end of said guides, and spring positioning plates fastened to said guide members adjacent said opening in the casing.

20 25 In testimony whereof I have affixed my signature.

JOHN C. MARTINE.
